UNITED STATES PATENT OFFICE.

WILLIAM T. HOLTON, OF RIVERSIDE, CALIFORNIA.

BOTTLE HOLDER OR SUPPORT.

SPECIFICATION forming part of Letters Patent No. 717,995, dated January 6, 1903.

Application filed May 5, 1902. Serial No. 106,065. (No model.)

To all whom it may concern:

Be it known that I, WILLIAM T. HOLTON, a citizen of the United States, residing at Riverside, in the county of Riverside and State of California, have invented new and useful Improvements in Bottle Holders or Supports, of which the following is a specification.

This invention relates to bottle holders or supports, and is primarily intended for supporting a nursing-bottle so as to be within easy reach of the child for which it is intended.

The peculiar manner of accomplishing the desired result, as well as the novel details of construction of the device, will be clearly set forth in the following description, reference being had to the accompanying drawing, in which the figure is a view in perspective, showing the device applied.

The numeral 1 designates a ring which fits over the neck of the bottle and is provided with an eye 2 at its top, to which is secured a laterally-extending supporting-bar 3, to be referred to hereinafter. A strand of wire 4 is connected to the ring 1 at a point on one side of the eyes 2 and runs longitudinally the position the bottle is to assume a suitable distance to form a bar 5, thence bent to form an eye 6, then curved downward in the form of an ellipse 7, the strand being bent to form a second eye 8, and finally terminating in a longitudinally-positioned bar 9, running parallel with the bar 5 and secured at its end to the ring 1 at a point opposite the bar 5 on the other side of the eye 2. The ellipse 7 constitutes an open ring, which is vertical and parallel with the ring 1, said elliptical portion forming a seat for the enlarged part of the bottle after the neck has been placed through the ring 1. In order to connect the ellipse 7 and the ring 1 together at their lower portions, I arrange a plurality of parallel longitudinal tie-rods 10, the ends of which engage the respective rings and, in conjunction with the bars 5 and 9, add rigidity to the bottle-support.

The reference - numeral 11 designates a hanger for the frame just described, which comprises a strand of wire bent intermediate its ends to form an eye 12 and provide two spring-jaws 13 and 14, which intersect each other, so that their ends 15 and 16 will have a tendency to spring together. The ends 15 and 16 are hooked to engage the eyes 6 and 8.

The supporting-bar 3, which engages the eye 2 of the ring 1, engages the eye 12 of the hanger 11, which is suspended from a suitable flexible connection 17, which is designed to be secured to any suitable support. When it is desired to incase the bottle within the holder, the hanger is removed from contact with the open ring or ellipse 7, and the bars 5 and 9 may be sprung apart enough to permit the bottle to be inserted, the neck being surrounded by the ring 1. The bars are then permitted to spring back, and the ends 15 and 16 are hooked in the eyes 6 and 8, making the holder complete. The tendency of the jaws 13 and 14 to spring together will result in holding the bars 5 and 9 in their correct positions, thus obviating the liability of the bottle becoming accidentally dislodged.

It will be obvious that changes in the size, dimensions, proportions, and minor details may be resorted to without in the least departing from the spirit of the invention.

Having thus fully described my invention, what I claim, and desire to secure by Letters Patent, is—

1. A bottle-holder comprising a ring adapted to fit over the neck of the bottle, an open ring a suitable distance therefrom and connected by parallel bars secured to the first and last named rings, a vertical spring supporting device secured to the open ends of the open ring, and a connection between the supporting device and the first-named ring.

2. A bottle-support comprising a pair of parallel rings one of which is open, bars connecting the open ring to the other ring, a supporting device normally holding the ends of the open ring against spreading, and a connecting means between the closed ring and the supporting device.

3. A bottle-support comprising a frame having an open ring at one end thereof, a supporting device comprising two spring-jaws removably secured to the ends of the open ring, and a connection between the supporting device and the opposite end of the frame.

In testimony whereof I affix my signature in presence of two witnesses.

WILLIAM T. HOLTON.
